UNITED STATES PATENT OFFICE.

SUMPTER LEE FLOWERS, OF BOULDER, COLORADO.

CHECK-CONTROLLED LOCK FOR LOCKERS.

1,180,993.

Specification of Letters Patent. Patented Apr. 25, 1916.

Application filed June 17, 1913. Serial No. 774,173.

To all whom it may concern:

Be it known that I, SUMPTER LEE FLOWERS, a citizen of the United States, residing at Boulder, in the county of Boulder and State of Colorado, have invented new and useful Improvements in Check-Controlled Locks for Lockers, of which the following is a specification.

The present invention relates to a check controlled lock for lockers or wardrobes or such like devices primarily intended for use in public places, such as theater lobbies, public halls, etc., and designed to receive the outer wraps, hats, umbrellas, etc., of the guests or patrons of the lobby and the primary object of the invention is the provision of simple but effective means arranged upon the locker or the door of the locker, whereby, upon the deposit of a coin or the like and the movement of a locking bolt, the door of the locker will be secured, and a "key" or "dummy" will be delivered to the operator, which "key" or "dummy" upon being redeposited will permit of the operation of the locking bolt to unlock the locker, and thus dispense with the service of an attendant, as well as assuring the operator that his wearing apparel is safely locked within the locker until required by the said operator.

With the above objects in view, and with others which will appear as the nature of the invention is more fully understood, the improvement resides in the construction, combination and operative arrangement of parts set forth in the following description and falling within the scope of the appended claims.

The essential features of the invention involved in carrying out the objects above stated, are necessarily susceptible of embodiment in various forms of construction without departing from the scope of the invention, but certain preferred and practical embodiments are exemplified by the accompanying drawings, in which:

Figure 1 is a general view of a plurality of locker compartments provided with the improvement, Fig. 2 is an enlarged vertical longitudinal sectional view taken through one of the lockers, Fig. 3 is an enlarged front elevation of the housing of the key-retaining and delivering apparatus, parts being in section, and illustrating the bolt in its locking position, Fig. 4 is a similar view but

illustrating the bolt moved to its unlocking position, Fig. 5 is a horizontal sectional view on the line 5—5 of Fig. 3, Fig. 6 is a detail vertical sectional view approximately on the line 6—6 of Fig. 5, Fig. 7 is a transverse sectional view on the line 7—7 of Fig. 3 looking in the direction of the arrow, Fig. 8 is a similar sectional view on the line 8—8 of Fig. 3 also looking in the direction of the arrow, Fig. 9 is a similar sectional view but illustrating the arm 56 contacted by a check or weight to move the tumbler to a position to permit of the passage of the reduced end of the lock bolt through the opening in the tumbler. Fig. 10 is a vertical sectional view looking toward the key chute, the said chute being partly broken away to illustrate the arrangement of the tumbler before the same is contacted by the key or dummy. Fig. 11 is a similar view showing the tumbler contacted by the key or dummy, Fig. 12 is a detail perspective view showing the L-shaped opening provided by the coin chute and casing to permit of the lateral movement of the tumbler when the said tumbler is swung by the weight of the coin, Fig. 13 is a perspective view of one of the tumblers, and Fig. 14 is a perspective view of the key.

Referring now to the drawings in detail, the numerals 1 designate a cluster of lockers or wardrobes which are adapted to be arranged permanently in a public place, such as, for instance, the lobby of a theater. Each of these lockers is provided with a hinged door 2 which is normally retained in a closed position by a suitable spring latch 3. The interior of the lockers are provided with suitable clothes hangers and hooks for the reception of the outer garments of a person or persons as well as for hats, umbrellas, etc. The lockers may be also provided with compartments for the reception of parcels, if desired.

While the latch 3 serves to sustain the door 2 in a closed position, it is desirable that the said door be locked after clothing has been deposited therein, so that the said clothing cannot be tampered with or removed by other than the authorized person or owner of the clothing. To accomplish this I provide each of the doors 2 with a suitable casing 4, which is preferably secured upon the inner face of the door or which may be arranged within a suitable

opening provided in the door, and which contains mechanism for securely locking the door upon the deposit of a coin to within the casing. The casing, it is to be understood, may be attached to the frame of the locker and have its locking element coöperate with a suitable keeper upon the door, but when the casing is applied directly to the door, as illustrated in the drawings, the same is arranged at a convenient point thereon and adjacent the edge of the door opposite to that hinged to the frame for the door. The frame, which may be designated by the numeral 5, is formed with a suitable recess or is otherwise provided with a keeper 6 for the reception of a locking bolt which is arranged within the casing 4, and which will presently be described.

The casing 3 is preferably provided with a removable face plate 7 which is slotted vertically adjacent its opposite upper corners to provide a "key" or "dummy" slot or opening 8 and a coin opening 9. The plate is further provided with a centrally arranged longitudinally extending opening 10 as well as with an opening 11 which is disposed at the lower left hand corner of the plate below the key opening 9, the said opening being surrounded by a cup or receptacle 12, the latter being preferably semi-spherical and having its edges secured to the face plate. The face plate may be further provided with a suitable inscription of the directions for operating the device.

35 The casing 4 is preferably of a rectangular formation and has its back provided with a hinged door 13 which is normally sustained in a closed position through the medium of a lock 14. The door 13 is arranged at the bottom of the casing and is adapted to provide means whereby access may be obtained to the mechanism within the casing as well as to remove a coin tray 15 from within the casing.

45 The opposite side members of the rectangular casing 3 are each provided with chutes 16 and 17 respectively. The chute 16 has both its upper and lower portions provided with inclined or angular extensions 18 and 19, the said extensions adapted to register with the openings 8 and 11. The chute 16 is substantially rectangular in cross section, but the opposite walls of the same may be provided with ridges or depressions which are adapted to coincide with similar ridges or depressions provided upon the "key" or "dummy" 20. The chute has its inner side enlarged, or otherwise supported a slight distance away from the side of the casing to which it is secured, and the vertically disposed member of the said chute has both its inner and outer walls or edges slotted, as at 21 and 22. The slot upon the outer edge of the chute is of a greater length than the slot 22 upon the inner edge of said chute, and

the inner wall of the chute, or the side thereof, secured to the casing, is provided with a slot or opening 23 which communicates with the vertically disposed slots 21 and 22, and whereby all of the slots provide a substantially L-shaped opening. Secured to the side of the casing is a flat spring 24 which is bowed toward the outer face of the chute 16 so that the said spring provides a bridging element or closure between the vertical slots 21 and 22 and the angular slot 23. The side of the casing, to which the spring and chute 16 is attached, and which may be designated by the numeral 25, is provided with a bolt opening 26 which is arranged a suitable distance forward of the said chute and spring. Pivots secured to the side 25, and adjacent the rear wall thereof, as designated by the numeral 27, is the elongated arm 28 of a lever tumbler 29. The tumbler has its arm 28 passing through the slots 21 and 22, and the said arm is of a width and thickness corresponding with that of the slot 23, so that the said arm may be received within the said slot 23 to provide a clear passage in the chute, in a manner and for a purpose presently to be described. The tumbler lever has an enlarged head 30, the said head being provided with a bolt opening 31 which is of a size and shape corresponding with the bolt opening 23 in the side 25 of the casing. The spring 24 is adapted to engage with the lever tumbler 29 to normally retain the same within the passage of the chute, and so provide the said chute with an obstruction or partition.

Pivots secured to the rear of the back member of the casing 3, as at 32, is a longitudinally disposed lever 33, the said lever having one of its ends contacting with the underface of the arm 28 of the lever tumbler forward of its pivot 27. The lever 33 has its opposite end provided with a weight 34, the said weight being adjustable, so that the pressure of the lever 33 upon the arm 23 may be regulated to compensate for the weight of the key 20, as will presently be set forth. The weighted lever 33, it will be noted, is adapted to swing the lever tumbler 29 upwardly of the chute 16, to cause its arm 28 to contact with the upper walls provided by the openings 21 and 22. The key 20 is of a sufficient weight to force the lever tumbler 29 downwardly within the vertical portion of the L-shaped opening, when the said key is deposited within the chute and contacts with the said lever tumbler. The tumbler is thus arranged directly opposite the angular portion or slot 23 of the L-shaped opening, and the bolt opening 31 of the tumbler is brought into register with the bolt opening 26 of the side 25 of the casing.

The chute 16, at a suitable distance below its L-shaped opening, has its face or side 35, which I will term its outer face, provided

with a transverse opening 36, the said opening being surrounded by an outwardly projecting cross sectionally rectangular guide-way 37 within which is arranged a slide 38. 5 The slide 38 is provided with an extending rod or arm 39 that is pivotally connected, as at 40, with a depending arm 41 provided upon a locking bolt 42. The locking bolt 42 is arranged within suitable bearings 43 upon 10 the inner face of the plate 7 of the casing and the said bolt is provided with a knob 44 which extends through the opening 10 in the plate 7, and whereby the said bolt may be moved longitudinally of the casing. The 15 bolt 42 is also provided with an upwardly extending member 45 that is connected with a plate 46, the said plate being arranged at an angle to the member 45. The plate 46 is provided with an elongated slot 47 and passing through the slot is a headed member 48 that serves as a guide for the plate. The 20 plate 46 is disposed within the path of the coin opening 9 in the face plate 7, and is adapted to serve as a closure for the said opening when the locking bolt has been moved in the direction of the opening.

The chute 17 has its upper extremity provided with an angular extension 49, the mouth of which being disposed opposite the 30 coin opening 9 of the plate 7, and the said chute is provided upon its front and rear faces or edges with openings 50 and 51, the opening 50 being arranged upon what I will term the outer edge of the chute and is of a greater length than the opening 51. The chute 17 is spaced a suitable distance away from the inner wall of the side 55 of the casing to which it is attached, and the inner side of said chute is provided with an opening 53 which enters the openings 50 and 51, and so providing the chute 17 with an L-shaped opening, similar to the opening in the chute 16.

The numeral 54 designates a spring which 45 is adapted to close the passages between the openings 50 and 51 and the right angular opening 53.

Pivotally connected to the side 55 of the casing is the arm 56 of a tumbler 57. The 50 arm of the lever extends through the openings 50 and 51, and is of a size adapted to be received within the opening 53. The spring 54 is adapted to exert a tension against the arm of the tumbler 57 to retain the said arm in the vertical portion of the L-shaped slot or opening in the chute. Pivotally secured to the back of the casing, as at 58, is a lever 59, the said lever having one of its ends arranged below the arm 56 of the tumbler, and forward of its pivot. The opposite end of the lever 59 is provided with a weight 60, so that the said lever normally forces the tumbler upwardly of the L-shaped slot of the chute 17, and into contact with the upper walls thereof. The weight 60 may

be adjustable, and the tumbler 57 is provided with an enlarged face which is also provided with a bolt opening 61. The side 55 of the casing is also provided with a bolt opening 62 which is disposed diametrically 70 opposite the bolt opening 61, and in a plane with the angular opening of the L-shaped slot or opening, as well as forward of the spring 54. The chute 17 has its outlet mouth disposed above the coin tray 15, so that the 75 coin from the said chute may be directed to within the tray.

The locking bolt 42 comprises an elongated member of a length slightly less than the length of the casing 4, and the opposite 80 ends of said bolt are provided with reduced portions 63 and 64 respectively, the said reduced portions being of a less diameter than the area of the bolt openings, and the said reduced portions provide the bolt with 85 shoulders 65 and 66 respectively.

It is to be understood that the weight 60 is adjusted upon the lever 59 to compensate for the weight of the coin to be delivered to within the coin chute, that is, the 90 coin is of sufficient weight to tilt the said lever.

It is to be understood that one of the reduced ends or fingers 63 or 64 is at all times received within one of the openings of one 95 of the enlarged heads of the lever tumblers and also that the springs 24 and 54 are of sufficient tension or strength to swing the said tumblers to within the vertical portions 100 of the L-shaped slots of the chutes, the lever tumbler not engaged by the bolt being under the influence of its weight lever and as a consequence forced upwardly of its L-shaped slot to bring its opening out of register with the opening upon this side of the 105 casing, and its enlarged face forming an abutment for preventing the movement of the locking bar in its direction.

We will now suppose that the key 20 is supported upon the slide 38 within the 110 chute 16, and that a person having deposited his clothing within a locker desires to lock the door of the same. He will insert a coin through the opening 9 to within the chute 17. The coin contacts with the arm 115 56 of the tumbler lever 57 and overbalances the weight lever 59, which brings the bolt opening 61 directly opposite the bolt opening 62 in the casing. The bolt is moved by its knob 44 toward the side 55 of the casing, and its reduced portion or finger 64 passes through the openings 61 and 62 and to within the keeper 6. The shoulder 66 of the bolt forces the arm 56 of the tumbler 57 to within the angular portion of the recess, thus permitting the coin to drop in the chute to within the tray 15. In the meantime, the slide 38 has been drawn out of the chute 16 to permit of the key gravitating to within the cup 12 from whence it 120 125 130

may be readily removed. This movement of the bolt further brings the plate 46 between the coin opening 9 and the mouth of the chute 17 to prevent the entrance of additional coins, and the reduced end or finger 63 of the bolt is brought out of engagement with the slot or opening 31 of the lever tumbler 29, permitting the said lever tumbler to be forced upwardly within the vertical portion of the L-shaped slot of the chute 16, and so bring its opening 31 out of register with the opening 26 of the side 25 of the casing, as well as bringing the enlarged head of said tumbler opposite the finger 63 of the sliding bolt to provide an obstruction or abutment to prevent the movement of the bolt toward the said lever tumbler 29. When the holder of the key desires to unlock the door to remove his articles from the locker, he inserts the key to within the key-opening 8 which passes to within the chute 16 and contacting with the arm 28 of the lever tumbler swings the same downwardly against the resistance offered by the weighted lever so that the bolt opening 31 of the head 30 registers with the bolt opening 26 in the side 25 of the casing. A movement of the locking bolt 42 toward the side 25 of the casing will permit of its reduced portion or finger passing through the bolt openings and its shoulder 65 contacting with the head of the lever tumbler 29 will force the arm of the same to within the angular portion of the L-shaped slot in the chute, and so permit of the key dropping upon the slide 38 which has thus been forced to within the chute 16. It will be noted that this movement entirely removes the finger 64 from the keeper 6, the bolt opening 62 and from the bolt opening 61 of the tumbler lever 57, permitting the arm 56 of the tumbler being forced into contact with the upper edges provided by the vertical portion of the L-shaped slot in the chute 17. The movement of the bolt further brings the shield 46 away from the coin opening 9 and the mouth of the coin chute 17. The device is thus set for the reception of an additional coin before the locking bolt can be moved to lock the door of the locker, as will be readily understood.

From the above description, taken in connection with the drawings, it will be noted that the device is simple in construction, thoroughly effective, and can be readily positioned upon any ordinary door. It will be further noted that the operation is simple, that the parts are so arranged as to perform their functions with ease and with accuracy, that the device requires little if any attention, and that the employment of the same entirely dispenses with the necessity of the employment of a clerk for checking deposited articles.

Having thus described the invention, what is claimed as new is:

1. In a device for the purpose set forth, a sliding locking bolt, pivoted members provided with enlarged heads and bolt openings, the bolt adapted to engage with one of the openings when in one position and to be in the path of the enlarged head of the second pivoted member to prevent the movement of the bolt in the direction of said member, and means for tilting the last named member to permit of the bolt passing through its opening, and permit the head of the first named member being swung to bring its opening away from the bolt and its head into abutting position with the bolt.

2. In a device for the purpose set forth, a longitudinally arranged sliding bolt, a coin chute and a key chute arranged at the opposite ends of the bolt, each of the chutes having an L-shaped opening, the key chute having a slide arranged below its L-shaped opening, pivoted tumbler levers passing through the L-shaped openings, weights for sustaining the tumblers in contact with the upper walls of the L-shaped openings, springs for forcing the tumblers against the outer walls of the chutes, each of the tumblers being provided with an enlarged head having a bolt opening, two weighted members comprising a coin and a key, the key adapted to be passed through the key chute to contact with the tumbler to bring its opening to register with the bolt to permit the sliding of the bolt and to force the tumbler against the pressure of the spring into the angular portion of the opening and to permit of the key dropping upon the slide, a connection between the slide and the bolt, and the weighted coin adapted to swing the tumbler in the coin chute against the influence of its weight to lower the head of the same and to bring the said tumbler directly opposite the angular portion of the L-shaped opening and to bring the opening of its head within the path of the sliding bolt, all substantially as and for the purpose set forth.

3. In a device for the purpose set forth, a casing having its opposite sides provided each with a chute, each of the chutes having an L-shaped slot, the sides of the casing forward of the chutes being provided with bolt openings, pivoted lever tumblers passing through the slots of the chutes, pivoted weight members co-acting with the lever tumblers for forcing the same upwardly of the slots, springs for forcing the tumblers within the vertical portions of the slots, each of the lever tumblers comprising an enlarged head having an opening which, when the tumbler is swung upon its pivot in a downward direction, is adapted to register with the bolt openings in the sides of the casing, the key chute having an opening

surrounded by a guideway, a slide arranged within the guideway, a key for the chute, said key adapted to be inserted in the key chute and to contact the tumbler to force 5 the same downward of the L-shaped slot and to bring the opening thereof into register with the key hole opening of the casing and to arrange the said tumbler adjacent the angular portion of the L-shaped 10 slot, a sliding bolt having its ends formed with reduced fingers providing shoulders, said slide connected with the bolt, one of the fingers of the bolt adapted to be passed through the registering openings of the 15 tumbler of the key chute and the casing and to have its shoulder contact with and force the tumbler into the angular portion of the slot and the slide to within the chute to permit of the key being received upon the 20 slide, the second finger of the bolt being disposed in the path of the head of the tumbler of the coin chute, a coin for the coin passage adapted to contact with the tumbler to bring the opening of its head into 25 register with the bolt opening upon this side of the casing and to permit of the sliding of the bolt in this direction to force the tumbler into the angular portion of the slot to allow the coin gravitating through the 30 chute and to move the slide out of the key chute to within its guide to permit of the key gravitating through the key chute.

4. In a check controlled lock for lockers including a coin chute and a key chute, a 35 pivoted tumbler extending through each of the chutes, each of said tumblers having a bolt opening, a slideable locking bolt between the tumblers and having one of its ends passing through the bolt opening in one of 40 the tumblers, independent means for tilting each of the tumblers to normally bring the bolt opening out of alignment with one of the ends of the bolt to retain the other end of the bolt in the bolt opening of the other 45 tumbler, and the said tumblers being arranged in the chutes in the path of contact with a key or a coin adapted to be moved thereby to bring the bolt opening thereof in alignment with the bolt to permit of the bolt 50 being slid out of engagement with the bolt opening in one of the tumblers through the bolt opening of the other tumbler.

5. A check controlled lock for lockers including a check chute having an ingress 55 opening at one of its ends and an egress opening at its other end, and a coin chute having an ingress opening at one of its ends, a

pivoted tumbler passing through each of the chutes arranged within the path of contact of the key or coin inserted in the said chute and adapted to be tilted by the weight of said key or coin, each of said tumblers having a bolt opening, a slideable bolt having one of its ends passing through the bolt opening of one of the tumblers, means for 60 tilting each of the tumblers to normally bring the bolt opening thereof out of alignment with the bolt to permit one of the tumblers being arranged in the path of contact with one of the ends of the bolt to sustain the opposite end of the bolt in engagement with the other tumbler, a slide in the key chute above the egress opening thereof, a connection between the slide and the bolt, 65 said slide adapted to be moved by the bolt out of the said chute when the bolt is passed through the opening in the tumbler of the coin chute.

6. A check controlled manually operated lock formed with a coin chute having an 80 ingress opening at one end thereof, and also formed with a check chute having an ingress opening at one of its ends and an egress opening at the other end thereof, pivoted tumblers one passing through each of the chutes, means for each of the tumblers for tilting the tumblers, spring means for normally retaining the tumblers in the chutes, each of said tumblers including a head portion having a bolt opening, a slideable bolt 85 having one of its ends passed through the opening in one of the tumblers and its opposite end out of alignment with the bolt opening but in the path of contact with the other tumbler, said bolt having its ends provided with shoulders adapted to contact with the tumblers to force the same out of the chutes when said bolt is arranged in the opening of either of said tumblers, a slide in the check chute above the egress opening 90 thereof, a connection between the slide and the bolt, said slide being arranged to be moved out of the check chute when the bolt has its end passed through the bolt opening in the tumbler of the coin chute and the said 95 bolt brought out of the opening in the tumbler of the check chute.

In testimony whereof I affix my signature in presence of two witnesses.
